INVENTOR

F. Kroeger

United States Patent Office.

F. KROECKER, OF NEW YORK, N. Y.

Design No. 3,780, dated December 7, 1869.

DESIGN FOR A PENDULUM-CLOCK-CASE FRONT.

The Schedule referred to in these Letters Patent and making part of the same

To all whom it may concern:

Be it known that I, F. KROECKER, of New York city, in the county and State of New York, have invented a new and original Design for Pendulum-Clocks; and I do hereby declare that the following is a full, clear, and exact description thereof, which will enable others skilled in the art to make and use the same, reference being had to the accompanying drawings, forming part of this specification.

The drawing represents a face view of my new clock.

This invention relates to a new design for pendulum-clocks, and consists in the employment of an oval

clock-case, which, on the line of the long diameter, contains the dial B and the pendulum-aperture C, as shown.

The distance between the centres of C and B may be varied, in accordance with the size of the dial and lower aperture.

I claim, as my invention—

The design for a pendulum-clock, as shown.

F. KROECKER.
